ELASTIC FLUID POWER PLANT

Bruno Hoffmann, Spandau, Germany, assignor
to General Electric Company, a corporation of
New York

Application January 21, 1937, Serial No. 121,653
In Germany February 17, 1936

5 Claims. (Cl. 60—11)

The present invention relates to elastic fluid power plants, especially to the arrangement of the auxiliaries of portable plants as are used on locomotives and aircraft.

5 The object of my invention is to provide an improved construction and arrangement of such power plants whereby they may be readily put in operation and economically operated.

For a consideration of what I believe to be 10 novel and my invention, attention is directed to the following description and the claims appended thereto in connection with the accompanying drawing.

The single figure of the drawing shows an 15 elastic fluid power plant arrangement embodying my invention as may be used advantageously for operating aircraft.

The power plant comprises an elastic fluid engine in the form of a steam turbine 10 for 20 driving a propeller 11. Elastic fluid is supplied to the turbine 10 from a boiler 12 having a heating element 13 connected to the turbine by a conduit 14. The exhaust fluid of the turbine 10 is conducted to a condenser of the radiator type 25 15, whence the condensate is discharged through a conduit 16 including a condensate pump 17 to a tank 18.

The auxiliaries for operating the power plant include in addition to the aforementioned condensate pump 17 boiler feed pumping means, in 30 the present instance shown in the form of two pumps 19 and 20, connected in series, and receiving operating medium, in the present instance water, through a conduit 21 from the tank 18. The discharge of the pump 20 is connected by a 35 conduit 22 to the inlet of the heating element 13. The auxiliaries further include a fuel pump 23 for conveying fuel from a tank 24 through a conduit 25 into a burner 26 forming a part of the 40 boiler. Air for maintaining combustion is forced into the burner by means of a blower 27 having a discharge conduit 28 connected to the burner 26.

As another auxiliary element for operating the 45 power plant I have shown in the present instance a lubricating pump 29 having an inlet conduit 30 connected to an oil tank 31 and a discharge conduit 32 for supplying oil to various elements 50 requiring oil under pressure during operation, such as bearings and servo motors (not shown).

In accordance with my invention, the auxiliaries 55 17, 19, 20, 23, 27, and 29 are divided into two groups, one of which is driven from the shaft of the turbine 10 and the other operated by means of a gas turbine receiving combustion gases dis-

charged from the boiler 12. More specifically, the pumps 19 and 20 are directly driven from the shaft of the turbine 10 and the pump 17 is driven from said shaft through the intermediary of bevel gears 33. The pump 23 and the blower 27 have a shaft 34 to which is secured a gas turbine wheel 35 driven by gases discharged from the boiler. The gases are directed to the wheel 35 by means of a nozzle diaphragm 36 and discharged from the wheel 35 into a flue 37. The shaft of the 10 pump 29 is driven from the shaft 34 through bevel gears 38. Thus, the primary drive means for the auxiliaries comprise the turbine 10 and the gas turbine 35, 36. To facilitate starting of the plant, I provide a secondary drive means or 15 motor shown in the form of a combustion engine 39 having a shaft 40 which may be coupled by means including a clutch 41 with the shaft of the pumps 19, 20 and by means including a clutch 42 with the shaft 34 of the pump 23. 20

During starting, the clutch 42 is engaged to cause operation of the pumps 23, 29 and of the blower 27 and thereby to supply fuel and air to the burner 26 and lubricant or actuating fluid to the bearings and servo motors. Thereafter, or 25 if desired, simultaneously the clutch 41 is engaged to cause operation of the pumps 17, 19, 20 and thereby to supply water to the boiler. As soon as the combustion has sufficiently developed to drive the gas turbine 35, 36, the clutch 42 is 30 disengaged, and finally upon operation of the turbine 10 the clutch 41 is disengaged.

In a preferred embodiment, as shown in the drawing, the pumps 17, 19, 20 are driven from the main turbine or prime mover in order automatically to change the supply of water to the boiler in response to changes of load on the turbine. The other auxiliaries are driven by the exhaust gas turbine because their operation depends primarily upon the load on the boiler. Furthermore, 40 the other auxiliaries including the pump 23 and the blower 27 are to be operated at first during the heating of the boiler. It is also for this reason more advantageous if they are driven by an engine, in the present instance, the gas turbine, which is ready for operation before the turbine 10 is operated.

Summarizing, the auxiliaries for operating a boiler, in the present instance a forced circulation type boiler, are divided into two groups, a 50 first group of essential auxiliaries including fuel and air supply means for the boiler, and a second group of other auxiliaries including pumping means for forcing the operating fluid through the boiler. The first group is normally operated 55

by a gas turbine arranged to receive exhaust gases from the boiler, and the second group is arranged to be driven by a prime mover or other power agency independent of the gas turbine. The two groups are started successively in their order aforementioned by means including a drive motor and clutches for separately connecting the drive motor to the groups. The drive motor is of relatively small size which is made possible by 10 the separate starting of the two groups. Once the first group including the essential auxiliaries has been started and combustion gases are formed in the boiler and supplied to the gas turbine, the latter takes over the operation of the 15 essential auxiliaries and the auxiliary drive motor becomes free to start the other auxiliaries.

What I claim as new and desire to secure by Letters Patent of the United States is:

1. Elastic fluid power plant including the combination of a prime mover, a boiler for producing elastic fluid to actuate the prime mover, auxiliaries including pumping means for forcing operating liquid into the boiler and other pumping means for forcing air and fuel into the boiler, 25 said auxiliaries forming two groups, means including the prime mover for driving one of said groups, means including a gas turbine receiving combustion gases from the boiler for driving the other group, and auxiliary means including a combustion engine and clutches for successively 30 starting the groups.

2. Elastic fluid power plant including the combination of an elastic fluid turbine, a condenser for receiving exhaust fluid from the turbine, a boiler connected to the condenser, auxiliaries including pumping means for forcing condensate from the condenser into the boiler and a fuel pump and a blower for forcing fuel and air into the boiler, said auxiliaries forming two groups,

one group including the pumping means being driven by the turbine, a gas turbine receiving combustion gases from the boiler for driving the fuel pump and the blower, and means for first starting the fuel pump and the blower and thereafter the pumping means, said means including a single drive motor and clutches for separately connecting the motor with each of said groups to permit successive starting of the groups by a relatively small drive motor. 10

3. Auxiliaries for operating a boiler comprising a first group of essential auxiliaries, a second group of other auxiliaries, drive means for normally operating the two groups, and means including a single drive motor for starting the 15 first and then the second group, the successive starting of the two groups permitting the provision of a relatively small drive motor.

4. Auxiliaries for operating a boiler comprising a first group of essential auxiliaries including 20 fuel and air supply means, a second group of other auxiliaries, drive means including a gas turbine for connection to such boiler for normally operating the first group, and means including a single drive motor and clutches for 25 successively starting the groups in the order aforementioned.

5. Auxiliaries for operating a forced circulation type boiler comprising a first group including fuel and air pumping means, a second group 30 including pumping means for forcing operating fluid into the boiler, a gas turbine arranged to receive exhaust gases from such boiler normally to drive the first group, a power agency independent of the gas turbine normally to drive the 35 second group, and means including a single drive motor for successively starting the two groups in the order aforementioned.

BRUNO HOFFMANN.
